US00D937243S

(12) **United States Design Patent** (10) Patent No.: **US D937,243 S**
(45) Date of Patent: **** Nov. 30, 2021**

(54) **SPEAKER**

- (71) Applicant: **Tempus Labs**, Chicago, IL (US)
(72) Inventor: **Brianna Gonzalez**, Chicago, IL (US)
(73) Assignee: **Tempus Labs**, Chicago, IL (US)
(**) Term: **15 Years**
(21) Appl. No.: **29/747,227**
(22) Filed: **Aug. 20, 2020**

Related U.S. Application Data

- (63) Continuation of application No. 29/693,538, filed on Jun. 3, 2019, now Pat. No. Des. 897,991.

(57) **CLAIM**

The ornamental design for a speaker, as shown and described.

DESCRIPTION

FIG. 1 is a bottom, front, and left side isometric view of a first embodiment of a speaker, showing my new design; FIG. 2 is a front elevational view of the speaker of FIG. 1; FIG. 3 is a rear elevational view of the speaker of FIG. 1; FIG. 4 is a left side elevational view of the speaker of FIG. 1; FIG. 5 is a right side elevational view of the speaker of FIG. 1; FIG. 6 is a top plan view of the speaker of FIG. 1; and, FIG. 7 is a bottom plan view of the speaker of FIG. 1. The dash-dash-dash lines are included for the purpose of illustrating portions that form no part of the claimed design. The dash-dot-dash lines are included for the purpose of illustrating boundary lines and form no part of the claimed design.

1 Claim, 7 Drawing Sheets
